United States Patent Office

Des. 226,630
Patented Apr. 3, 1973

226,630

REFUSE CONTAINER CLOSURE

Phillip J. Gentile, 16301 Knollwood Ave., Granada Hills,
Calif. 91344, and James L. Shannon, 7914 Greenbush
Ave., Van Nuys, Calif. 91402

Filed Feb. 7, 1972, Ser. No. 224,397

Term of patent 14 years

Int. Cl. D7—06

U.S. Cl. D49—35

FIG. 1

FIG. 2

FIG. 3

FIG. 4

FIG. 1 is a perspective view of a refuse container closure showing our new design;

FIG. 2 is a front view partially in section thereof;

FIG. 3 is a left-side view, the right-side being substantially a mirror image thereof; and

FIG. 4 is a bottom plan view thereof.

We claim:

The ornamental design for a refuse container closure, as shown.
